UNITED STATES PATENT OFFICE.

CHARLES E. DURYEA, OF PEORIA, ILLINOIS.

DRIVE-CHAIN.

SPECIFICATION forming part of Letters Patent No. 657,526, dated September 11, 1900.

Application filed November 22, 1899. Serial No. 737,841. (No model.)

To all whom it may concern:

Be it known that I, CHARLES E. DURYEA, a citizen of the United States, residing at Peoria, in the county of Peoria and State of Illinois, have invented certain new and useful Improvements in Drive-Chains; and I do hereby declare the following to be a full, clear, and exact description of the invention, such as will enable others skilled in the art to which it applies to make and use the same.

My invention relates to that class of drive-chains consisting of thin side links held together by rivets pivoted in bearings provided in connecting-blocks; and the objects of my invention are to secure light weight, long life, easy and noiseless operation, and other minor objects, such as will be brought out in the following specification.

In the accompanying sheet of drawings, forming part of this specification, Figure 1 is a plan view of a portion of a completed chain. Fig. 2 is a sectional elevation through the center of the chain.

Similar letters refer to similar parts in both views.

The general design of this chain is common to first-class bicycle and other chains, and consists of thin side pieces D D, commonly stamped from sheet metal of suitable thickness and quality and connected by pivots E E. These pivots are provided with an enlarged bearing portion lying between the side links D D and serving to fix the distance between said links. It is customary to rivet or otherwise fasten these pivots E E firmly into the links D D, so that no movement, with consequent wearing, occurs between the two, thus causing all movement between the respective chain parts to take place between the bearing-surface of pivot E and its corresponding surface in the bearing-block. This bearing-block is of suitable shape to fit sprocket-teeth and is provided at each end with pivot-holes through which the pivots E E pass and in each case receive a suitable journal-bearing. I provide in this block a more or less cylindrical opening passing nearly or quite through it in a direction transverse to the axes of the pivot-holes, and this opening is of a greater diameter than the distance between said pivot-holes and is placed midway between them, so that it intersects both pivot-holes

slightly. This chamber is likewise placed midway of the block with respect to its sides, and sufficient metal for carrying the strain to which the chain may be subjected is left at the sides of the block. This chamber may not pass completely through the block, but it is preferable to construct it as shown in the drawings. These figures indicate a cylindrical hole B, formed by an ordinary drill with angular point, but not carried full size completely through the block. Such an opening serves as a chamber for absorbent filling C, which can be inserted in the chamber, but cannot be pushed through it, because the chamber is not full size throughout.

It is my practice to place the blocks so that the large open end of the chamber is next the face of the sprocket-wheel, and the filling C projects more or less therefrom and serves to lessen the metallic click commonly found in chains as they run on metallic wheels, and also reduces the vibrations and resonance of the chain parts themselves. This filling is saturated with oil or any preferred lubricant, which it feeds to the pivots E E at the points of intersection B B of the chamber with the pivot-holes and also to the face of the sprocket-wheels.

By having an opening, although small, on each face of the block lubricant may be introduced into the filling from either side of the chain, which is a feature of considerable importance when the inner or large opening of the chamber is not accessible because of the chain being on a sprocket or in similar inaccessible position.

It will be readily seen that the contracted end of the chamber prevents accidental displacement of the filling C due to dirt or similar obstructions getting between the block and the face of the sprocket. It will also be seen that the absorbent filling serves as a filter for the lubricant, which is fed to the pivots E E at their centers in a regular manner and in good condition. From there it works naturally outward toward their ends and tends to carry grit and dirt out of the bearings instead of in the reverse direction, as occurs with chains of similar design as now used. The absorbent substance being more or less elastic has no tendency to fall out of the end of the holes. The outer

end is partly closed, because any dirt on the sprocket-face would otherwise force the substance *c* out of the hole outward. It will also be readily seen that a large chamber passing through the chain-blocks makes them lighter and permits them to be hardened more evenly than is possible with thin portions outside the pivot-holes and a thick solid body between them. Multiple chambers may be used, if preferred.

Having thus described my invention, I claim—

1. In a drive-chain link, a bearing-block, having pivot-holes in opposite ends thereof, a cylindrical chamber between said holes transverse thereto and of larger diameter than their distance apart and an absorbent filling for said chamber.
2. In a drive-chain a bearing-block, having a central cylindrical chamber and parallel pivot-holes transversely and oppositely intersecting same and an absorbent filling for said chamber.
3. In a drive-chain a bearing-block having

a central opening circular in cross-section 25 and contracted in area at one end, filled with an absorbent material and intersected on opposite sides by transverse pivot-holes.

4. In a drive-chain a bearing-block having a chamber open at the vertical bearing-face 30 and a noise-reducing material filling said chamber.

5. In a drive-chain a bearing-block having a chamber open at the vertical bearing-face, an absorbent noise-reducing material filling 35 in said chamber and transverse pivot-holes intersecting same.

6. A drive-chain bearing-block having transverse pivot-holes and a cylindrical chamber at right angles thereto with both 40 ends open and the one end reduced, substantially as and for the purpose specified.

In testimony whereof I affix my signature in presence of two witnesses:

CHARLES E. DURYEA.
